UNITED STATES PATENT OFFICE.

WILLIAM M. SMITHER, OF KEENE, KENTUCKY.

TRACE-CARRIER.

SPECIFICATION forming part of Letters Patent No. 293,807, dated February 19, 1884.

Application filed November 12, 1883. (No model.)

To all whom it may concern:

Be it known that I, WILLIAM M. SMITHER, a citizen of the United States, residing at Keene, in the county of Jessamine and State of Kentucky, have invented certain new and useful Improvements in Trace-Carriers, of which the following is a specification, reference being had therein to the accompanying drawings.

10 This invention relates to trace-chain carriers for plow and similar harness; and its objects are to carry the chain, to provide a means for holding the back-band in place, and to prevent the driving-lines from being caught or interfered with. I accomplish these objects by means which will be hereinafter set forth.

To enable those skilled in the art to make and use my invention, I will proceed to describe its construction and operation.

20 In the accompanying drawings, making part of this specification, Figure 1 represents a plan view of the carrier attached to the back-band, and also a section of chain. Fig. 2 represents a longitudinal section of one side of the carrier and back-band.

In the figures, A represents the back-band of plain plowing-harness, made in any of the well-known and usual ways.

B represents the body of the carrier, which 30 may be struck up of sheet metal; but I make it, preferably, of malleable iron. This carrier consists of a single plate of metal, a portion of the metal at the top and middle being removed or omitted for lightness. From the metal cut away at the center of the plate sufficient is left to form a tongue, D. The plate is bent in such manner that its lower end will be doubled under the upper portion, thus forming two loops, e e, through which the

chain passes. The tongue D, it will be seen, is 40 bent inward, so that it cannot only be made to catch into the links of the chain, but will obviate any danger of the lines catching when they drop upon the outside of the loops. The plate is bolted or riveted to the band A by the 45 rivets x' x, the rivet x' confining the two portions of the plate and the band together at the same time. The back portion of the loops lying against the band, all wear and tear on said band is prevented. When the chain is adjusted to a desirable position, one of its links is caught on the tongue D, and thus the band is prevented from slipping out of place. When the hook is not in use, the chain will simply run freely between it and the body of the plate. 55 The tongue is curved, as represented in Fig. 2, and one side of the link lying in the concave side of the tongue, it (the link) is kept more securely in place.

Having thus fully described my invention, 60 what I claim as new, and desire to secure by Letters Patent, is—

As an article of manufacture, a trace-carrier constructed, as herein described, of a single piece of metal having formed upon it a 65 corrugated tongue, two unbroken supporting-loops, and its lower end curved under and projecting upward, and adapted to be secured to the body of the carrier and to the back-band of the harness by the same rivets, substantially 70 as described.

In testimony whereof I affix my signature in presence of two witnesses.

WM. M. SMITHER.
